UNITED STATES PATENT OFFICE.

JOHN C. RINGE, OF BRIDGEPORT, CONNECTICUT, ASSIGNOR TO THE SINGER MANUFACTURING COMPANY, A CORPORATION OF NEW JERSEY.

STRIP GUIDING AND CONTROLLING ATTACHMENT FOR SEWING MACHINES.

1,422,808.

Specification of Letters Patent.

Patented July 11, 1922.

Application filed February 11, 1918. Serial No. 216,482.

To all whom it may concern:

Be it known that I, JOHN C. RINGE, a citizen of the United States, residing at Bridgeport, in the county of Fairfield and State of Connecticut, have invented certain new and useful Improvements in Strip Guiding and Controlling Attachments for Sewing Machines, of which the following is a specification, reference being had therein to the accompanying drawings.

This invention relates to an improvement in strip-guiding and -controlling devices for use in connection with sewing machines.

The invention has for its primary object to improve that type of strip-controlling devices in which one or both edges of a strip of material are deflected from the path of the needle or needles of a sewing machine by the provision of simple and effective means for deflecting the edge or edges of the strip without movement of the strip-guide or any part thereof. Another object of this invention is to provide a strip-guiding and edge-deflecting attachment capable of being applied to any sewing machine without material alteration of the sewing machine or parts thereof.

In its preferred embodiment, the invention comprises a strip-guiding and -controlling device supported by a base-plate 30 pivotally mounted upon the cloth-plate of a sewing machine and secured against movement when in operative position. Adjustably supported by the base-plate and in advance of the needles is a strip-guide adapted 35 to fold or hem the edges of a strip of material. Supported in bearings upon the base-plate is a rock-shaft carrying convergently arranged edge-diverting arms terminating in smoothing fingers and normally positioned above the strip. The rock-shaft is adapted to be manually actuated to lower the edge-diverting arms into engagement with the strip between the delivery end of the strip-guide and the needles and by means 40 of the pressure of the arms inclined to the direction of feed to deflect or divert the edges of the strip from the path of the needles.

This strip-controlling device is particularly adapted for use in connection with the application of a strengthening and seam-covering strip to the juncture of the bib and body or nether part of overalls. To that end an edge-guide for the body garment is 45 carried by the strip-guide and an edge-

folder is adjustably secured upon the base-plate to fold and guide the edge of the bib in superposed relation with respect to the body garment.

In the accompanying drawings, Fig. 1 is 60 a front side elevation of a sewing machine and of the improved attachment applied thereto. Fig. 2 is a plan view of the attachment and a portion of the sewing machine to which it is applied, with the edge-diverting arms in ineffective position. Fig. 3 is 65 a plan view of a portion of the attachment indicating its position relatively to the presser-foot and needles of the sewing machine and illustrating the edge-diverting arms in effective position. Fig. 4 is a front end elevation of a portion of the sewing machine and of the improved attachment. Fig. 5 is a 70 detail view in perspective of one of the edge-diverting arms. Fig. 6 is an inverted view 75 of the bib, body and seam-covering strip illustrative of their relative arrangement and indicating the result of deflecting a portion of the seam-covering strip from the path of the needles.

The sewing machine shown in the drawings is as usual constructed with a base 1 and an overhanging bracket-arm 2, terminating in the head 3, in which is journaled the needle-bar 4, carrying the spaced needles 5 and 6 and the presser-bar 7, carrying the presser-foot 8.

Mounted upon the cloth-plate 9 of the sewing machine is the strip-guiding and -controlling attachment comprising a base-plate 10 pivotally secured by means of a screw 11 and yieldingly held against the cloth-plate by means of a coiled spring 12 interposed between the base-plate of the attachment and the head of the screw 11. The 95 base-plate 10 is further secured upon the cloth-plate against accidental movement by means of the screw 13. Adjustably secured upon the base-plate 10 by means of screws, as 14, and a clamping plate 15 is a slotted 100 arm 16 sustaining the strip-guide 17 adapted to fold the edges of the strengthening or reinforcing strip 8 normally guided into the path of the needles.

Secured upon the base-plate 10 by screws, 105 as 18 and 19, are spaced bearings 20 and 21 for a rock-shaft 22. Rigidly secured upon the rock-shaft 22 in the desired positions by means of set-screws, as 23 and 24, are convergent edge-diverting arms 25 and 26, ter- 110

minating in smoothing-fingers 27 and 28 directed toward each other. The smoothing-fingers 27 and 28 are of less thickness than the convergent arms, thereby providing 5 guiding surfaces, as 29, for the diverted folded edges of the strip *s*. Secured upon the rock-shaft by set-screws, as 30, is a hand-operated member 31, normally held against the base-plate 10 by means of the 10 flat-spring 32 to position the edge-diverting arms 25 and 26 above and clear of the strip *s*. By lifting the member 31 against the action of the spring 32, the consequent actuation of the rock-shaft causes the arms 15 25 and 26 to engage the strip *s* beyond the delivery end of the strip-guide and by means of the pressure of the arms inclined to the line of feed to divert the folded edges thereof from the path of the needles. 20 It is of course obvious that for certain classes of work either one of the arms 25 and 26 may be omitted when it is desired to divert or deflect only one edge of a strip.

Carried by the strip-guide and preferably formed integral therewith is an edge-guide 33 adapted to guide the edge *m'* of the body material *m* in superposed relation with respect to the strip *s* and into the path of the needle 6. Adjustably secured upon the base- 25 plate 10 by means of screws, as 34, and a clamping plate 35 is the slotted supporting arm 36 of an edge-folder 37 having an edge-turning scroll 38, more particularly for folding and guiding the edge *b'* of the bib-section *b* of overalls, in superposed relation with respect to the body material *m*.

While the edge-diverting device described herein is particularly adapted for use in connection with applying a strengthening- 40 and seam-covering strip to the juncture of the bib and body sections of overalls and obviating the necessity of ripping out the stitches for the purpose of folding-in the end of the strip, it is equally applicable for 45 other classes of work and it is to be understood that the invention is in nowise limited to the particular class of work described.

Having thus set forth the nature of the invention, what I claim herein is—

50 1. A strip-controlling attachment for sewing machines, comprising a strip-guide, edge-diverting means adapted to act upon an edge of a strip beyond the delivery end of said strip-guide and divert said edge from its normal course, and means independent of said strip-guide for at will rendering said edge-diverting means effective.

60 2. A strip-controlling attachment for sewing machines comprising a strip-guide adapted to fold the opposite edges of the strip, edge-diverting means constructed and arranged to act upon the folded edges of a strip beyond the delivery end of said strip-guide and divert said edges from their normal course, and means independent of said

strip-guide for at will rendering said edge-diverting means effective.

3. A strip-controlling attachment for sewing machines comprising a strip-guide, an edge-diverting device independent of and outside the field occupied by said strip-guide, means for normally holding said edge-diverting device out of operative engagement with a strip, and manually operable means for actuating said edge-diverting means to place it into effective engagement with an edge of said strip for diverting the latter from its normal course. 75

4. A strip-controlling attachment for sewing machines, comprising a strip-guide, convergently arranged edge-diverting arms normally held out of engagement with a strip, and operative connections for at will actuating said arms to divert the edges of the strip from their normal course. 80

5. A strip-controlling attachment for sewing machines, comprising a strip-guide, an edge-diverting arm inclined with respect to the longitudinal axis of said strip-guide, and means independent of said strip-guide 90 for placing said arm into contact with an edge of a strip beyond the delivery end of the strip-guide to divert the latter from its normal course.

6. A strip-controlling attachment for sewing machines, comprising a strip-guide, and an edge-diverting arm inclined with respect to the longitudinal axis of said strip-guide and adapted to divert an edge of said strip from its normal course, said arm including 100 an edge-deflecting surface and a strip-smoothing surface. 95

7. A strip-controlling attachment for sewing machines, comprising a strip-guide, a rock-shaft, an edge-diverting arm carried by 105 said rock-shaft, means for normally holding said edge-diverting arm out of operative engagement with the strip, and manually operated means for actuating said rock-shaft to throw said edge-diverting arm into effective engagement with said strip. 110

8. A strip-controlling attachment for sewing machines, comprising a strip-guide, and a movable edge-diverting arm adapted to act directly upon the folded edge of a strip beyond the delivery end of said strip-guide to divert said edge from its normal course. 115

9. An attachment for sewing machines, comprising a strip-guide adapted to fold the edges of a strip, a rock-shaft, an element 120 actuated by said rock-shaft and adapted to engage and deflect a folded edge of said strip beyond the delivery end of said strip-guide, and manually operated means for actuating said rock-shaft. 125

10. An attachment for sewing machines including, in combination, a strip-guide, means adapted to be brought into action independently of the strip-guide to act upon the edge of a strip beyond the delivery end 130

of said strip-guide for diverting the edge of the strip from its normal course, an edge-guide, and an edge-folder.

11. An attachment for sewing machines including, in combination, a strip-guide adapted to fold the edges of a strip passed therethrough, a rock-shaft, converging edge-diverting arms carried by said rock-shaft and inclined with respect to the longitudinal axis of said strip-guide, manually operated means for actuating said rock-shaft, an edge-guide and an edge-folder.

In testimony whereof, I have signed my name to this specification.

JOHN C. RINGE.
